UNITED STATES PATENT OFFICE

153,145

DESIGN FOR A DISPENSING BEVERAGE
CONTAINER

David Godorov, Philadelphia, Pa.

Application August 6, 1947, Serial No. 140,739

Term of patent 3½ years

(Cl. D2—3)

To all whom it may concern:

Be it known that I, David Godorov, a citizen of the United States, and residing at Philadelphia, in the county of Philadelphia, Commonwealth of Pennsylvania, have invented a new, original, and ornamental Design for Dispensing Beverage Container, of which the following is a specification, reference being had to the accompanying drawing, forming part thereof.

I claim:

The ornamental design for a dispensing beverage container, as shown.

DAVID GODOROV.
